UNITED STATES PATENT OFFICE.

JACOB F. KOHLER, OF NEW YORK, N. Y., ASSIGNOR TO JONICK SIRKEN CO., INC., A CORPORATION OF NEW YORK.

DESIGN FOR A CEILING PLATE FOR LIGHTING FIXTURES.

Application filed July 16, 1925. Serial No. 14,119. Term of patent 3½ years.

To all whom it may concern:

Be it known that I, JACOB F. KOHLER, a citizen of the United States, residing in New York city, county and State of New York, and doing business at 143 East 23d Street, in said city, have invented a new, original, and ornamental Design for a Ceiling Plate for Lighting Fixtures, of which the following is a specification, reference being had to the accompanying drawing, forming part thereof.

Figure 1 is a bottom plan view showing my design, only a portion of the ornamentation being shown complete, it being understood that the remaining portion involves a mere repetition of the part more fully illustrated; and

Figure 2 is a side elevational view showing my design.

I claim:

The ornamental design for a ceiling plate for lighting fixtures as shown.
